UNITED STATES PATENT OFFICE.

FRANK W. LAROM, OF BROOKLYN, NEW YORK.

DESIGN FOR A GLOVE-BUTTONER.

SPECIFICATION forming part of Design No. 18,783, dated December 4, 1888.

Application filed November 1, 1888. Serial No. 289,772. Term of patent 14 years.

To all whom it may concern:

Be it known that I, FRANK W. LAROM, a citizen of the United States, residing at Brooklyn, in the county of Kings and State of New York, have invented and produced a new and original Design for a Glove-Buttoner, of which the following is a specification.

This design has for its object to provide a novel glove-buttoner, as hereinafter described and claimed, reference being made to the accompanying drawing, in which the figure is a plan view of the buttoner.

In the drawing it will be seen that the buttoner is composed of the tapering loop A, extending from one end of a handle, B, representing a forearm, which bears the representation of a hand, C, the fingers of which extend in a direction opposite to the tapering loop.

The representation of the forearm may be provided with a bracelet, D, and the fourth finger of the hand may have a ring, E.

What I claim is—

The design for a glove-buttoner, consisting of the handle B, representing a forearm and bearing the hand C, and the tapering loop A, extending from one end of the forearm opposite the hand, substantially as shown and described.

In testimony whereof I have hereunto set my hand and seal in the presence of two subscribing witnesses.

FRANK W. LAROM. [L. S.]
